UNITED STATES PATENT OFFICE.

WILLIAM DIETER, OF BROOKLYN, NEW YORK.

TORPEDO DEPTH-GEAR.

1,369,169.

Specification of Letters Patent. Patented Feb. 22, 1921.

Application filed November 30, 1920. Serial No. 427,361.

To all whom it may concern:

Be it known that I, WILLIAM DIETER, a citizen of the United States of America, residing in the borough of Brooklyn, county 5 of Kings, city and State of New York, have invented certain new and useful Improvements in Torpedo Depth-Gears, of which the following is a specification.

This invention relates to an improvement 10 applicable to the depth gear or depth engine of an automobile torpedo, the purpose of which is to correct the existing tendency of a torpedo to dive at the end of a practice run, which oftens results in the loss of the 15 torpedo.

Many torpedoes are lost after practice runs because they fail to come to the surface. When the air is shut off at the end of the run the torpedo drops in speed very 20 rapidly, coming down from 30 to 20 knots within a half second. This causes the pendulum of the depth steering gear to swing forward at first, which of itself tends to give an up rudder which would cause the 25 torpedo to steer upward; but this is followed instantly by the recoil swing of the pendulum, which (with the diaphragm of the depth gear in a position of equilibrium) gives the down rudder, and as the torpedo 30 still is under considerable speed, this causes it to quickly steer downward, so that in shallow water it is liable to bury its nose in the mud lying on the bottom and be stuck fast. If this is averted the buoyancy of 35 the torpedo will in time bring it to the surface.

At the next instant the pendulum again swings forward, due to the nose of the torpedo being inclined downward, which should 40 cause an up rudder, which will tend to bring the torpedo toward the surface; but in actual practice this is defeated by the fact that the air having been cut off, the steering engine ceases to function about this 45 time and consequently it fails to turn the rudder up and leaves the torpedo headed down. In torpedoes as built, the effort is to provide for this failure to steer by the introduction of a "broaching spring" which 50 tends constantly to turn the rudder up, and which is supposed to act when the steering engine ceases to function, so as to leave the rudder upturned; but in actual practice it often happens that the broaching spring 55 fails to overcome the friction of the stuffing boxes at opposite ends of the depth engine,

so that the friction in these boxes holds the depth engine fast, and keeps the rudder in the position to which it was last turned, and if this happens to be a down rudder 60 the torpedo is sure to dive. Owing to this many torpedoes have been lost.

The present invention seeks to overcome this disadvantage by affording a prolonged supply of air for the depth engine sufficient 65 to keep it functioning long enough to enable it to control the rudder until the spasmodic actions due to the pendulum movements have passed. This is accomplished by providing an air chamber between the reducing valve and the depth engine, in which a 70 charge of compressed air is stored, which air serves to feed the depth engine after the air valve is closed at the end of the run.

The invention also includes a spring inlet 75 valve to this chamber, the primary object of which is to act as a check valve to prevent back-flow from the chamber when the air supply valve is closed; a secondary object is to partly throttle the air and thereby reduce 80 its pressure, so that the depth engine, particularly at starting, will not be affected by too sudden an inrush of air. This reduction of pressure also effects economy in the expenditure of air. 85

The invention also includes means for draining off from the air chamber any water which may accumulate therein. The air chamber, with this provision, prevents water being driven over into the depth engine, which heretofore has sometimes occurred, and which results in deranging the 90 performance of the depth engine.

The invention is shown in its preferred embodiment in the accompanying drawings, 95 wherein—

Figure 1 is a side elevation of the after-part of a torpedo, partly in vertical mid-section, the contained apparatus being shown in a diagrammatic arrangement, so 100 that the relations of the parts may be seen;

Fig. 2 is a vertical section through the air chamber on a larger scale, in planes indicated by the line 2—2 in Fig. 3;

Fig. 3 is a vertical section through the air 105 chamber in a plane at right angles to Fig. 2, being on the line 3—3 in Fig. 2.

Referring first to Fig. 1 of the drawings, A is the hull or shell of the torpedo, of which B is the compressed air flask or reservoir, C is the starting valve, D is the pressure reducing valve, and E, as a whole, is 110

the depth mechanism or depth gear. This mechanism comprises a pendulum *a* hung at *b* from a fixed point within the torpedo, a diaphragm *c* exposed on its under side to water pressure, and on its upper side to the stress of a spring *d*, only part of which is shown, a depth engine *e*, and horizontal rudder *f*. The depth engine is of the usual construction employed in automobile torpedoes, having a pilot valve working inside the piston or plunger; this pilot valve is operated by a valve stem *g* which is controlled in its movements both by the pendulum *a* and the diaphragm *c* in the usual manner. This control is commonly accomplished by mechanism which is here shown diagrammatically, the pendulum being connected by a rod *h* to the lower arm of a lever *i*, the middle of which is connected by a link *j* to an elbow lever *k* pivoted at *l* and connected at *m* to the diaphragm; the upper arm of lever *i* is connected to the valve rod *g*. It results that any movement of either the pendulum or diaphragm is communicated to the valve rod, so that if the longitudinal axis of the torpedo is otherwise than level, the effort of the pendulum is to cause the depth engine to steer in such direction as to bring the torpedo to a level; and if the torpedo is above or below the set depth, the displacement of the diaphragm up or down acts to so operate the depth engine as to tend to steer to a lower or higher level until the proper depth is reached. The internal piston or plunger of the depth engine is connected by a piston rod *n* and connecting rod *p* with the tiller *q* of the rudder *f* in the usual manner.

The compressed air from flask *B* is admitted through pipe 5 and, when the starting valve *C* is open, through pipe 6 to the reducing valve *D*, and the air under reduced pressure is admitted through pipe 7 to the turbine or other engine for driving the torpedo (the driving mechanism not being shown). From the pipe 7 or other convenient means carrying air under reduced pressure, a pipe 8 is led which commonly communicates directly with the inlet 9 of the depth engine *e*. According to the present invention, however, an air chamber *F* is introduced in the pipe 8, the portion of the pipe leading from chamber *F* to inlet 9 being marked 10.

The construction of chamber *F* is best shown in Figs. 2 and 3. The air from pipe 8 enters at 11, forcing open a spring-pressed valve 12, and passing up through tube 13 to the upper part of the chamber *F*. The valve 12 is suitably guided upon its seat, being pressed thereto by a spring 14 which reacts against a plug 15 which may be removed through an opening 16 in the hull or shell *A* of the torpedo to get access to the valve. The valve 12 serves not only as a

check valve to prevent backflow of air from chamber *F* and to hold air trapped in the chamber after the inflow ceases, but also serves to somewhat reduce the pressure of the air entering the chamber, this reduction in pressure depending upon the stress of the spring 14. It is unnecessary to make this spring adjustable, as it is quite feasible to make it of wire of suitable stiffness and impart to it suitable compression by the screwing home of the plug 15, so that it exerts the required stress against the valve 12. The valve 12 and spring 14 are located in a chamber 17 having from its upper side an outlet through the tube 13, as stated. The tube 13 projects up within the chamber *F* high enough to be above any water which may by any possibility accumulate within the chamber during a run of the torpedo.

The chamber *F* is of suitable capacity to hold a sufficient reserve of compressed air to supply the depth engine with air at suitable pressure sufficient to accomplish several reversals of movement of the depth engine, so as to keep this engine operative during the period of disturbance which occurs at the end of the run of the torpedo. In actual practice an air chamber having a diameter of about two and one-half inches, and a length of about three and one-half inches, will ordinarily suffice, these dimensions being given merely as illustrative of one suitable size, it being understood that the chamber may be made of greater or smaller capacity, as experience may determine. 100

Heretofore difficulty has sometimes been experienced by reason of water accompanying the compressed air and being driven into the depth engine, whereby its performance has become irregular. This disadvantage is overcome in the present invention by the introduction of the air chamber *F*, which serves as a pocket to receive any water, which separates by gravity from the air; and by the provision of means for draining this chamber at the end of a practice run, so as to free it from water before the next run. Such draining may be accomplished by hand, but is preferably done by automatic means; and for this purpose a drainage valve 29 is provided, shown in Fig. 3, which consists of a valve seating against a seat 21 at or near the bottom of the chamber, this seat communicating through an internal passage with a drainage outlet 22. The valve has a stem 23 that is pressed upward by a light spring 24 housed in a chamber 26. During the run the compressed air admitted to the chamber *F* holds this valve closed, so that neither air nor water can escape. At the end of the run, however, when the air pressure falls, the spring 24 lifts the valve until stopped by a pin 28 applied to the valve stem 23, or by any other appropriate stop. 120 125 130

ping means, whereupon the accumulated water flows out through the outlet 22 into the torpedo body.

The construction shown and described is considered the preferable one for carrying out the invention, but obviously this construction may be greatly varied within the limits of practice, and the invention is to be understood as susceptible of any variation within the scope of the appended claims.

I claim as my invention:—

1. In a torpedo the combination with depth mechanism, including a depth engine 15 and a source of compressed air for feeding such engine, of an air chamber introduced between such source and the inlet to the engine, adapted to store compressed air sufficient to actuate the engine after the source 20 of air is cut off.

2. The combination of claim 1, with a check valve at the inlet of air to the air chamber for preventing back-flow therefrom.

3. The combination of claim 1, with a spring-pressed valve at the inlet of air to 25 the air chamber, whereby to reduce the pressure of the air entering such chamber.

4. The combination of claim 1, the air chamber having means for introducing the air to its upper part, and having the outlet 30 for air from its upper part, and a space beneath for receiving water, whereby any water is separated from the air.

5. The combination of claim 1, the air chamber having in its lower part means 35 for draining off accumulated water therefrom.

6. The combination of claim 1, the air chamber having at its lower part an automatic drainage valve adapted to close under 40 internal pressure, and having a spring to open it when the pressure is relieved, whereby to drain off accumulated water.

In witness whereof, I have hereunto signed my name.

WILLIAM DIETER.
